UNITED STATES PATENT OFFICE.

HENRY A. CHEVOLA, OF NEW YORK, AND CHARLES B. MOSSI, OF BROOKLYN,
NEW YORK.

BRACKET FOR DOORS.

Application filed May 14, 1921. Serial No. 469,745.

To all whom it may concern:

Be it known that we, HENRY ALEXANDER CHEVOLA and CHARLES B. MOSSI, citizens of the United States of America, residing at 5 Bronx, borough of Manhattan, city, county, and State of New York, and Brooklyn, county of Kings, State of New York, respectively, have invented certain new and useful Improvements in Brackets for Doors, 10 of which the following is a specification.

This invention relates to brackets for doors.

More particularly, this invention relates to brackets for doors of ovens and the like 15 and has for its object to provide improved means for automatically moving the door to its closing position and for retaining the door in its fully opened position.

In accordance with our invention, the 20 most preferred form thereof comprises a pair of brackets for enclosing a spirally coiled spring coacting with a lug carried by the oven door for automatically closing the oven door upon release and for frictionally holding the door in its fully opened 25 position against the action of such closing spring.

Further features and objects of the invention will be more fully understood from 30 the following description and the accompanying drawings, in which—

Fig. 1 is a detail perspective view of 35 range oven embodying our invention, showing the oven door in its closed position;

Fig. 2 is a view similar to Fig. 1, showing the oven door in its fully open position;

Fig. 3 is a detail, inner face elevation of 40 the bracket per se on an enlarged scale;

Fig. 4 is an outer edge view of Fig. 3;

Fig. 5 is an outer face elevation of Fig. 3 and

Fig. 6 is an inner edge view of Fig. 3.

Referring to Figs. 1 and 2, the oven is 45 indicated generally at 10; the oven door 11 is shown pivoted at its lower edge by means of the oppositely disposed, pivot lugs 12, received respectively in suitable openings 13, see Fig. 3, of the oppositely related brackets 14.

As indicated in Figs. 3 to 6, inclusive, each bracket is a hollow casting and com-

prises a body casting the inner edge 15 of which is cast integrally with the outer face 16, in turn cast integrally with the outer edge portions 17, 18, 19. The outer plate 20 is shown of a separate casting and is positioned on the body casting of the bracket by means of the set screws 21, tapped into the curved partitions of the body 60 casting. Such separable construction of the plate 20 affords ready access to the interior of the curved slot 22 formed in the casting between the upper outer edge of the circular portion 17 and the inner circular partition 23, indicated in Fig. 3, whereby the spirally coiled spring 24 may be readily inserted within its curved housing 22. Upon positioning the plate 20 on the body casting of the bracket, the spring 24 is 70 located to coact with one of the oppositely projecting lugs 25, extending laterally of the door 11 through the circular slot 26 of the housing 22.

In Fig. 3 we have shown the position of 75 the spring 24 when the oven door 11 is fully closed, the lug 25 of the oven door 11 in such position being located at the head of the housing 22. Upon manually forcing the door 11 toward its open position, the coil 24 is more and more compressed and the lug 25 of the oven door 11 is moved along the slot 26 and approaches the rear of the housing 22.

Horizontally arranged adjacent the rear 85 of the opening 26, we provide the friction, spring pressed means 27 for retaining the door 11 in its fully open position, as is indicated in Figs. 3 and 4 and 5; such retaining means 27 in the construction illustrated comprises the housing member 28 secured by the set screws 29 to the outer face 17 of the body casting of the bracket, within which housing 28 is received the pin 30 having the pointed or reduced head 31 projecting beyond the housing 28 and pressed by the coiled spring 32, see Fig. 4, adjustably held within the housing 28 by means of the threaded plug 33. Upon moving the oven door to its fully open position 100 as indicated in Fig. 2, the lateral edge of the door 11 engages the head 31 of the pin 30 forcing the same interiorly of the housing 28 and against its spring 32, where-

by the door is frictionally held by lock pin 30 against movement under the action of the coiled closing spring 24.

Upon forcing manually or by means of the foot the door 11 upwardly, the door will be released from frictional engagement with the oppositely disposed pins 30 and is automatically closed by the springs 24 of the brackets in its fully closed position.

10 Such bracket construction affords a convenient support for the gas pipe 35, leading to the burners 36 of the oven, as by means of the yoke member 37 constructed, see Figs. 3 and 5, to be countersunk on 15 the edge face portion 18 and held in position by means of the retaining screws 38.

The bracket is advantageous in that the same is of markedly reduced over-all dimensions, is rigid in construction and capable of enclosing stout springs of relatively short length. Our construction is also 20 advantageous in that the same can be readily mounted adjacent the hinge or pivot of the door and does not extend within the 25 range of movement of the hand or foot of the operator.

The invention is also of advantage in lending itself to ornamental outline, in marked contrast to closure members heretofore proposed.

Whereas we have described our invention by reference to specific forms thereof it will be understood that many changes and modifications may be made from the spirit

of the invention as defined by the appended 35 claims.

We claim:

1. The combination with a door of an oven or the like, said door being provided with a hinge lug, of a bracket having an 40 opening for receiving said hinge lug, said bracket comprising a recessed member, a coil spring disposed within said recessed member and coacting with said oven door for closing the same and spring-pressed retaining means carried by said bracket for holding the oven door in its fully opened 45 position.

2. The combination with a door of an oven or the like, said door being provided 50 with a hinge lug, said door being further provided with an extension element, of a bracket having an opening for receiving said hinge lug, said bracket comprising a curved recessed member, said member having an opening having a curved lateral opening receiving said extension element, a curved coil spring disposed in said curved recessed member and coacting with said extension element for closing the same and 55 spring-pressed retaining means carried by said bracket for holding the oven door in its fully opened position.

In testimony whereof we have signed this specification this 4th day of May, 1921.

C. B. MOSSI.
H. A. CHEVOLA.
